(57) **CLAIM**

The ornamental design for a cage for use in an oil infusion device, as shown and described.

DESCRIPTION

FIG. 1 is a perspective view of the cage showing the new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a perspective view showing the cage maintaining the shape of a bag that is configured to receive material to be infused into oil.

The broken lines depict environment and constitute no portion of the claimed design.

1 Claim, 8 Drawing Sheets
